UNITED STATES PATENT OFFICE.

HARRY G. CRAIN, OF CANISTEO, NEW YORK, ASSIGNOR OF ONE-HALF TO JOHN P. LAIR,
OF CANISTEO, NEW YORK.

MAGNETIC STENCIL AND WORK HOLDER.

Application filed July 15, 1926. Serial No. 122,718.

This invention relates to magnetic stencil and work holders, and belongs particularly to the type or class of devices for holding iron or other material which has been so treated that it can be attracted and held by magnetism when made up in the form of a stencil. The object of this invention is to provide a magnetic holder that will attract strongly and firmly press all portions and lines of the stencil on the work, especially at the edges of the stencil in order that none of the fluid applied may creep under the edges of the stencil and prevent a clear, clean line of demarcation. Such stencils and this invention may be used upon any material which may be coated, lettered or decorated with paint, varnish, lacquer or other liquid or partly liquid coating, by hand brushing, air brushing, spraying or other method for applying the same. It may be used for applying pigment or colors of various kinds of fusible materials which have been colored to any desired shade, and which may be applied as paste, powdered enamel or glass or other like substances which upon being fused become sufficiently fluid to be applied adherently to the material acted upon. The purpose is to form letters, figures, decorations and the like, and is intended primarily for use in the manufacture of signs, or upon articles displayed.

This invention consists of magnets, usually electromagnets having pole pieces of special construction and arrangement as illustrated in the accompanying drawings making a part of this application. Figure 1 of the drawings represents a top plan view showing the usually preferred shape and disposition of the pole pieces. Figure 2 is a cross-section on the broken line 2—2 of Figure 1.

Throughout the description and drawings the same number is used to refer to the same part.

Considering the drawings, numeral 1 marks a soft iron box-like magnet, having pole pieces 2 projecting and spaced apart inwardly at the top of the side or end of the box. The divisions 3 are legs of the magnet and have the pole pieces 4 projecting upon opposite sides and spaced apart as shown.

Cores 5 provided with laterally projecting pole pieces 6 at the top are surrounded with the coils 7. The cores 5 may be secured side

by side to the bottom of the box 1 by screws 8 or in any convenient manner.

It will be noted that the outer or uppermost surfaces of the pole pieces all lie in the same plane, affording a supporting surface 66 for the work 9, upon which rests the stencil 10 of magnetic material. The stencil introduces a path for the lines of magnetic polarization between opposite poles and pole pieces of the magnet, and it will be observed that the pole pieces are arranged near together with the object of making the magnetic effect as strong as possible, in order that all the edge portions of the stencil 10 may be tightly held in continuous contact with the 70 work 9.

It will be understood that this invention is not limited to any special size of the magnet or to the particular form of the pole pieces illustrated which may clearly be varied within the purview of the appended claims. Nor, is it intended to confine this invention to a magnet whereof the poles or pole pieces lying in the same plane constitute a flat surface upon which the material 80 to be marked is held. The surface may clearly be curved if demanded by any considerable amount of work demanding the construction of a special holding surface for the work. The construction herein shown 85 and described is found in practice to successfully attain the object stated, which is to strongly hold the stencil body and edges at all points closely upon the work, thereby preventing the marking fluid whatsoever it 90 may be from creeping and acting against the formation of a sharp, clean edge to the matter stencilled.

Having now described this invention and explained the mode of its operation, what 95 I claim is:

1. In a magnetic stencil and work holder, the combination with electro-magnets provided with off-set pole pieces formed with alternately projecting and recessed portions, 100 the projecting portions of the pole pieces of one magnet arranged in the recessed portions of the pole pieces of the adjacent magnet, the said pole pieces being disposed near each other to create a strong magnetic field, and the outer surfaces of the said pole pieces being located in the same plane to provide a surface for holding the work to be stencilled.
2. In a magnetic stencil and work holder, the combination with an electro-magnet hav- 110

ing one portion provided with pole pieces projecting on opposite sides and spaced apart, the said magnet having side portions provided with projecting spaced pole pieces 5 extending between the said pole pieces of the first mentioned portion, and the outer surfaces being located in the same plane to provide a surface for holding the work to be stencilled.

10 3. In a magnetic stencil and work holder, the combination with an iron box having therein a series of electro-magnets arranged side by side, the poles of the said magnets

having pole pieces constructed with alternately projecting and recessed portions on opposite sides, the projecting portions of the pole pieces of the magnets and the sides of said box extending into the recessed portions of the pole pieces of the adjacent magnet, the said pole pieces being located near each other 15 to create a strong magnetic field, and the outer surfaces of the said pole pieces being arranged in the same plane to provide a surface for holding the work to be stencilled.

In testimony whereof I affix my signature.
HARRY G. CRAIN.
